CRIB TOY MOBILE

Jorma Vennola, Princeton, N.J., assignor to Columbia
Broadcasting System, Inc.

Filed Feb. 16, 1973, Ser. No. 333,354

Term of patent 14 years

Int. Cl. D21—01

U.S. Cl. D34—15 J

FIG. 1

FIG. 2

FIG. 3

FIG. 4

FIG. 5

FIG. 1 is a side elevational view of a crib toy mobile showing my new design;

FIG. 2 is a rear elevational view thereof;

FIG. 3 is a top plan view thereof;

FIG. 4 is a bottom plan view thereof; and

FIG. 5 is a front elevational view thereof.

I claim:

The ornamental design for a crib toy mobile, substantially as shown.
